UNITED STATES PATENT OFFICE

172,123

ELECTRICAL SOLDERING GUN

Jack J. Barbour, Philadelphia, Pa., assignor of one-half to Weller Manufacturing Company, Easton, Pa., a limited partnership, and one-half to Weller Manufacturing Company, Inc., Bayamon, P. R., a corporation of Puerto Rico

Application September 10, 1953, Serial No. 26,761

Term of patent 14 years

(Cl. D26—1)

To all whom it may concern:

Be it known that I, Jack J. Barbour, a citizen of the United States, residing at city of Philadelphia, in the county of Philadelphia and State of Pennsylvania, have invented a new, original, and ornamental Design for an Electrical Soldering Gun, of which the following is a specification, reference being had to the accompanying drawing, forming part thereof.

Figure 1 is a side elevation of an electrical soldering gun, showing my new design, the opposite side being the same.

Figure 2 is a top plan view thereof;

Figure 3 is a front elevational view thereof;

Figure 4 is a rear elevational view thereof; and

Figure 5 is a section view taken along the lines 5—5 of Figure 1.

The dominant features of my design reside in those portions shown in full lines.

I claim:

The ornamental design for an electrical soldering gun, as shown and described.
